INVALID GARMENT

Myrtle M. Turnham, Minneapolis, Minn.

Application January 29, 1951, Serial No. 208,367

4 Claims. (Cl. 128—287)

1

This invention relates to new and useful improvements in invalid garments, and more particularly to such garments designed for use for semi-ambulatory or bedridden patients who experience difficulty with the control of their bodily excretory functions.

The hospitalization and treatment of patients require oftentimes the use of invalid garments or bed protectors in conjunction with the treatment of senile, paralyzed, or very ill patients who have, for one reason or another, lost control over their bodily excretory functions and have become involuntary or incontinent. Involuntary excretion or incontinence has long provided a problem in the care and treatment of patients, and there has been a great need for a garment which may be used for the control thereof which is facile and sanitary, being easily removable for changing or cleaning and not painful to apply to the patient.

It is therefore an object of the present invention to provide a sanitary protector for the use of invalid patients which may be adjusted to the body with a minimum of discomfort.

It is a further object of this invention to provide a sanitary garment for invalid patients having means for holding a disposable liner therein which may be easily and readily removed for cleaning or changing thereof.

It is a further object of this invention to provide a sanitary invalid garment which may be frequently and readily changed with a minimum of pain and discomfort to the patient.

A further object of this invention is to provide a waterproof acid resistant garment having non-absorbent characteristics which may be tightly yet comfortably positioned around an invalid patient for the absolute containment of excretory wastes therein, having a removably sanitary liner therein, and breathing means whereby air is not cut off from the portion of the body enclosed by the garment.

Further objects of this invention reside in the novel construction of the garment and the means for holding the sanitary liner therein.

Other and further objects of the present invention are those apparent and inherent in the article as claimed, described and drawn.

The invention will be described with reference to the drawings in which corresponding numerals refer to the same parts and in which:

Figure 1 is an isometric view of the instant invention showing one leg of the garment in closed or wearing position and the other leg of the garment in open position;

Figure 2 is a sectional view taken along the line 2—2 of Figure 1;

Figure 3 is a top plan view of the garment showing the same in flat or unfolded position before it is positioned upon the wearer, and showing the absorbent liner in dotted lines;

Figure 4 is a view similar to Figure 3, but showing a modified form of the present invention;

Figure 5 is a sectional view similar to that of

2

Figure 2, but showing the modified form of the present invention as illustrated in Figure 4;

Figure 6 is an isometric view of a second modified form of the present invention; and

Figure 7 is a sectional view taken along the lines 7—7 of Figure 6.

Referring now to the drawings, particularly to Figure 3, the garment generally designated 10, is shown comprising two sections: a rear section 11 and a front section 12. These two sections combine and form the complete garment as may be best seen with reference to Figure 1. The rear section 11 is provided with a waist band 13 having snap elements 14, 15 and 16, and 17, 18 and 19 thereon. These snap elements cooperate with snap elements 20 and 21 on the front section of the garment to form a completed snap as shown at 22 in Figure 1. The waist band 13 is folded back upon itself at the ends 23 and 24 thereof for a short distance. Thus, end 23 is maintained in folded position by the penetration of snap element 14, and end 24 is maintained in folded position by the penetration of snap element 19. In addition ends 23 and 24 may be maintained in this folded position by sealing or other means, as desired.

Rear section 11 is provided with leg hems or bands 26 and 27. The length of bands 26 and 27 is such that when attached to bands 55 and 56, as shown for 55 in Figure 1, bands 26 and 27 will be caused to bulge slightly outward and provide a space as shown in Figure 1 for the admission of air to the patient's body within the confined section. This provides air circulation or "breathing" to this section of the patient's body with all of its attendant comfort. Secured to leg band 26 are strap elements 28 and 29, and secured to leg hem 27 are strap elements 30 and 31. These elements are attached at the inner end thereof to their respective leg hems, as is shown at 32 for strap element 29, and may be sewed, sealed, adhesively secured, or otherwise fastened to the leg hem. Strap elements 28 and 29 of rear section 11 cooperate with strap elements 33 and 34 of front section 12, and strap elements 30 and 31 of rear section 11 cooperate with strap elements 35 and 36 of front section 12 to form ties or bows, as illustrated at 38 and 39 in Figure 1.

The rear section 11 is formed from a single sheet of material and has the configuration best shown in Figure 3, having a somewhat trapezoidal body section and integral crotch sections 40 and 41 which depend therefrom. The rear section 11 is also provided with a bottom hem 42 and a second bottom hem 43. Bottom hem 42 extends continuously along the bottom of rear section 11 over seam 30' and then continuously along the top of front section 12. Hem 43 extends similarly. Hem 42 is provided with snap elements 44, 45 and 47. Hem 43 is provided with snap elements 48, 49 and 50. Elements 44, 46 and 47 cooperate with snap element 51, fastened on hem 42 on front section 12 to form a snap, as illus-

trated at 52 in Figure 1. Likewise, snap elements 48, 49 and 50 cooperate with snap element 53 on front section 12 to form a complete snap similar to that shown at 52.

Rear section 11 is seamed to front section 12, as indicated by seam 30'. Front section 12 is provided with waist hem 54 and leg hems or bands 55 and 56, similar to those described with reference to rear section 11, but of slightly shorter length. Section 12 is also made from one flat piece and, as shown in Figure 3, has a configuration somewhat like the cross section of a basket with upending portions along seam 30' to form crotch portions 43 and 41.

As was mentioned previously, section 11 is joined to section 12 along seam 30'. Retaining sections 57 and 58, shown in Figure 3, are joined at the outer edges 59-61 and 62-64 thereof to front and rear sections 12 and 11. Thus, these two retaining sections are similar in form but reversed in position. Sections 57 and 58 face inwardly and are sewed, sealed or otherwise secured to sections 11 and 12 along edges 59-61 and 62-64, respectively, as shown in Figure 3. This sealing extends inwardly but a short distance and hence there are formed opposed pocket openings at 67 and 67' in rear section 11, and 68 and 68' in front section 12, which openings extend continuously from front to rear and through the crotch, as best shown in Figure 3. These pockets thus serve to accommodate the opposed edge portions of an absorbent inner disposable liner 69, shown in dotted lines in Figure 3 and full lines in Figure 2. The liner extends therein to approximately the position shown by the dotted line 79 at the sides of the garment, and extending downwardly from the crotch of the garment to substantially the bottoms of the tubular leg portions of the garment adjacent to the crotch, as indicated at X and Y in Figure 1.

The retaining members 57 and 58 are shown joined together by a strap 71 a narrow flat strap member 71 which serves to aid in retaining liner 69 in proper position in the crotch of the garment. It may be noted that strap 71 is secured to crotch portions 41 and 40 at 72 and 73, on the interior surface thereof.

It may be seen that whenever consistent with sanitary construction, that all seams have been eliminated or covered and that thus a very comfortable garment is formed for the patient. The position of the ties shown at 38 and 39 for the legs and the triple snap elements on section 11 cooperating with a single snap element on section 12, form ready adjustments for the waist, as indicated by snap 22, and for the legs, as indicated by snap 52.

The garment is commonly made of what is known in the trade as "plastic." Thus, for example, plastic materials such as nylon are readily desirable for this sort of garment. It is to be understood that other types of plastic may be used without departing from the spirit and scope of this invention. The plastic is all electronically welded at seams, edges and bindings. No rough edges are allowed to protrude anywhere or to cause irritation to the skin. Thus, all seams or hems such as hems 13, 26, 21 and the like are of one piece, and are folded over the edges of the garment so as to seal the same. No elastic is provided in the garment to cut the circulation. This is an important feature when the patient is continually confined to bed and bodily functions are impaired. It may be noted that all the adjustments, for example, those on the waist line

and the leg bands are provided for in the preferred form by the use of snaps and that no safety pins or other sharp objects are used in either the garment or the sanitary liner.

The pocket formed on the inside of the garment by retaining members 57 and 58 is positioned so as to adequately cover the legs and the excretory organs whether the garment be applied to a man or a woman. Thus, the portion of the pocket upon the rear section 11 of the garment is high, considerably wider, and the portion of the pocket on the front section of the garment 12, high, but somewhat narrower. The pockets are all sealed to the garment so that they cannot leak.

The sanitary inner liner is composed of disposable cellulose cotton or other absorbent material, and is prevented from slipping around by the retaining members 57 and 58 and strap 71. It may be noted in connection with the pocket on the front section of the garment 12 that it extends substantially upwardly on the groin as to make this equally utilitarian protection for men as well as for women. When open, as shown in Figure 1, the garment is flat, or substantially so, when placed upon a bed beside the patient. A pad is put in the sanitary liner as shown by the dotted lines in Figure 3, and the patient is then rolled onto the garment. Front section 12 is brought up between the legs and fastened on the sides of the front, as shown with reference to Figure 1, by snap 22 and by tapes 38 and 39 and snap 52.

When the garment is closed the fitted crotch sections 41 and 42, make it similar to a pair of pants. This provision of the fitted crotch also helps to hold the sanitary liner up where it is desired and gives width across the legs so that there will be no leaking therefrom. It may be noted that since the garment is made of plastic and is waterproof, it is also air-proof, and the ties at 38 and 39 are provided so as to allow a slight gap between the leg seams when the garment is in position for the wearer's body so as to let sufficient air inside. The provision of fastening the garment on the legs and at the front thereof makes it easier for the nurses or nurses' aides to adjust the garment and also makes it extremely more comfortable for the patient for he may lie on his back or sides and will not encounter the snaps or ties.

Referring now to Figure 4, a modified form of this garment is shown wherein snap elements are used to close the leg sections together instead of the tie elements shown in Figure 3. Thus, each one of the snap elements in Figure 4, corresponding to a tie element in Figure 3, is given a number similar to that of the tie element of Figure 3, but with an a added thereto. Thus, snap element 29a of Figure 4 corresponds to tie element or strap 29 of Figure 3. The garment of Figure 4 is substantially similar to that shown in Figures 1-3 but is composed of a loosely woven fabric or mesh-like material 74 throughout the major portion thereof, as indicated by the mesh-like cross sectioning on that figure. Any loosely woven fabric of cotton, rayon, "nylon" etc. may be used but it has been found that it is advantageous to make the fabric of quick-drying thread such as "nylon" thread. The hems in this instance are of the same material, although it is to be understood that they may be made of a different type material without departing from the spirit and scope of this invention, and are sewed to the main body sections 11 and 12 by stitching which is indicated by the dotted stitch-line 75 on Figure 4. Each one of these snap-ele-

ments is provided with a protecting square of heavier material as shown at 76 for snap 29a. Snap element 29a is fastened to this strip of heavier or protecting material 76 and then strip 76 is sewed to hem 26, as indicated by stitch line 77. The protecting material for the snaps is the same in each instance and the construction is also the same. With reference to the snap elements provided on the waist band 13 and the leg bands 42 and 43 of section 11, the snap elements are fastened upon a single strip of protective material or tape as shown at 78 and 79. Thus, as a matter of actual construction, the snap elements for use in this type of garment are usually formed on a continuous tape and sections cut out as needed. In the type of construction shown in Figure 4, the material 74 is sewed and seamed together at 80 for section 11 and 81 for section 12. The material 74 extends throughout 15 11 and 12 only to the juncture along seams 82-84 in section 12, and 85-87 in section 11. 20

The retaining element in Figure 4, generally designated 88, comprises rear section 93 which is superimposed on a supporting fabric constituting the body of the garment, by seams 85-87 and front section 94 also superimposed on a supporting fabric constituting the body of the garment, in material 74 and bounded by seams 82-84. The two sections are joined together at 91 and 92 to form a continuous sanitary liner containing member. A cover or containing member 96 is provided for section 93 and a cover or retaining member 95 is provided for section 94. These two cover sections are attached together at 91 and 92 and are of the configuration shown in Figure 4, whereupon a circular aperture 90 is provided in section 96, and a somewhat oval aperture 99 is provided in section 95. It may be noted that the two apertures join at the edges thereof to provide a continuous aperture of the configuration shown, whereby a sanitary liner may be inserted and retained against sections 93 and 94 by the action of covers 96 and 95. Thus, there is provided a water and acid resistant pouch composed of two plies along the side edges thereof and having an aperture in the center. This pouch is composed of the same acid and water resistant materials mentioned before in conjunction with the form shown in Figures 1-3. This form of my invention is adapted to be used in substantially the same manner as described with reference to the form of Figures 1-3.

A second modified form of the present invention is shown in Figure 6. This form of the invention is designed specifically for use with very still or weak patients.

The garment 99 in this case comprises a flat bottom sheet 98 of water and acid resistant characteristics, and a cover sheet 108 sealed thereto along the edges thereof and at corners 104-107, and provided with an aperture 109 therein. Disposed within the aperture in Figure 6 is shown a sanitary liner 115 of which a cross section is shown in Figure 7. Thus, it may be seen that this modification provides substantially a rectangular base resistant section 98 of material with a cover section 108 having a central aperture 109 therein sealed thereto along the edges 111-114 and corners 104-107 thereof, cross member tapes or hems 111 and 112 sealed along two sides thereof and extending the length of the rectangular section, and parallel tapes 113 and 114 along the remaining sides thereof having end extensions 100-103 which may be tied around the body of the wearer or around protrud-

ing sections on a hospital bed for the anchoring of said garment.

As many differing embodiments of this invention may be had without departing from the spirit and scope thereof, it is to be understood that I do not limit myself to the specific embodiment described herein.

I claim as my invention:

1. An excretion resistant and retaining garment for invalids adapted to be applied to the body by folding and securing therearound comprising in combination two body sections, a rear body section at least a portion of which is made of material resistant to human excretions and a front body section at least a portion of which is made of such resistant material, said rear body section when laid out in open position comprising a flat member bordered at the top thereof by a substantially horizontal waist band with fastening elements attached at the ends thereof, thigh band members extending downwardly and outwardly from said horizontal waist band and bordering the sides of said rear body section, downwardly depending portions disposed on either side of a center crotch section, leg closure bands extending along the bottom edge of said rear section and along said downwardly depending portions and along the bottom edge of said front section, said front section comprising a flat member when laid out in open position comprising a center crotch section secured to the center crotch section of said rear section, upwardly extending portions similar to said downwardly depending portions adjacent said center crotch section on said rear section and secured to said downwardly depending portions, downwardly and inwardly disposed thigh band members extending along the side edges of said front body section adapted for cooperation with the thigh band members on said rear section, and a horizontal front waist band member adapted for cooperation with the waist band member on said rear section, means disposed on said front waist band member cooperable with means disposed on said rear section whereby said waist bands may be connected together at a point between the thigh and the groin of the wearer, means disposed on the thigh band sections of the rear sections and the thigh band sections of the front section, whereby said front and said rear thigh band portions may be connected at a point between the hip and the groin of the wearer, means disposed on the leg closure band sections of the front section and the leg closure band sections of the rear section whereby a leg closure may be formed with the juncture of the closure at a point between the thigh and the groin of the wearer, all of said closure means being adapted to provide a flap closure extending from waist band to leg closure band over each leg at a point between the hip and the groin of the wearer, said closure being adapted for the opening thereof whereby said front section may be folded upwardly or downwardly for application to or removal from the body of said invalid, a retaining pouch comprising retaining elements secured upon said front and rear sections, said retaining elements each comprising an excretory resistant member sealed along the outer edge thereof and disposed vertically on said rear section and extending along the edge of said depending and upwardly depending portions downwardly on to said front member, said retaining elements forming a pouch for the insertion of a disposable sanitary liner, said retaining elements connected at the

inner edges thereof by a flat strap, said strap located over the juncture of the crotch element of the front section and the crotch element of the rear section.

2. An excretion resistant and retaining garment for invalids adapted to be applied to the body by folding and securing therearound comprising in combination two body sections, a rear body section at least a portion of which is made of material resistant to human excretions and a front body section at least a portion of which is made of such resistant material, said rear body section when laid out in open position comprising a flat member bordered at the top thereof by a substantially horizontal waist band with fastening elements attached at the ends thereof, thigh band members extending downwardly and outwardly from said horizontal waist band and bordering the sides of said rear body section, downwardly depending portions disposed on either side of a center crotch section, leg closure bands extending along the bottom edge of said rear section and along said downwardly depending portions and along the bottom edge of said front section, said front section comprising a flat member when laid out in open position comprising a center crotch section secured to the center crotch section of said rear section, upwardly extending portions similar to said downwardly depending portions adjacent said center crotch section on said rear section and secured to said downwardly depending portions, downwardly and inwardly disposed thigh band members extending along the side edges of said front body section adapted for cooperation with the thigh band members on said rear section, and a horizontal front waist band member adapted for cooperation with the waist band member on said rear section, means disposed on said front waist band member cooperable with means disposed on said rear section whereby said waist bands may be connected together at a point between the thigh and the groin of the wearer, means disposed on the thigh band sections of the rear sections and the thigh band sections of the front section, whereby said front and said rear thigh band portions may be connected at a point between the hip and the groin of the wearer, means disposed on the leg closure band sections of the front section and the leg closure band sections of the rear section whereby a leg closure may be formed with the juncture of the closure at a point between the thigh and the groin of the wearer, all of said closure means being adapted to provide a flap closure extending from waist band to leg closure band over each leg at a point between the hip and the groin of the wearer, said closure being adapted for the opening thereof whereby said front section may be folded upwardly or downwardly for application to or removal from the body of said invalid, a pouch for the insertion of a removable sanitary liner therein, said pouch comprising a resistant section located on the rear section of said garment, having a covering member with an aperture disposed therein, a front resistant section disposed on the front section of said garment having a covering member having an aperture therein, the aperture in said front covering member and the aperture in said rear covering member being joined at the edges thereof so as to form a continuous aperture which will substantially cover the excretory organs of an invalid.

3. An invalid's garment having front and rear portions each having a waist edge, said waist

edges being adjustably cooperable for the forming of a waist-encircling member, said front and rear portions each having a crotch edge and being joined together thereby, said front and rear portions also having downwardly extending side edges and means for connecting the side edges of said rear portion to the corresponding side edges of said front portion to form tubular leg portions, at least a part of each of said front and rear garment portions being resistant to body excretions, vertically disposed retaining elements secured to the inner surfaces of said front and rear garment portions along their outer and top edges and extending across the juncture of said crotch edges, said retaining elements being resistant to body excretions and cooperating to form a pouch for receiving the opposed side portions of a disposable sanitary liner, said retaining elements being connected at their inner edges by a flat strap, said strap being located over the juncture of the crotch edges of said front and rear garment portions.

4. An invalid's garment having front and rear portions each having a waist edge, said waist edges being adjustably cooperable for the forming of a waist-encircling member, said front and rear portions each having a crotch edge and being joined together thereby, said front and rear portions also having downwardly extending side edges and means for connecting the side edges of said rear portion to the corresponding edges of said front portion to form tubular leg portions, at least a part of each of said front and rear garment portions being resistant to body excretions, vertically disposed retaining elements secured to the inner surfaces of said front and rear garment portions along their outer and top edges and extending across the juncture of said crotch edges, said retaining elements being resistant to body excretions and cooperating to form opposed inwardly facing pocket members extending upwardly from the lower inner portions of said tubular leg portions to the uppermost ends of said retaining elements, said retaining members being adapted to receive the opposed marginal side portions of a disposable sanitary liner or pad and cooperating to removably support said pad in position in the crotch of the garment with its side edge portions extending downwardly into the bottoms of said pocket members at the lower inner sides of the tubular leg portions of the garment, whereby said pad may completely cover the excretory organs of a patient's body and prevent leakage from the garment at the inner sides of the legs, when the garment is worn by an ambulatory patient and a laterally extending portion disposed above and adjacent to the crotch seam and connected to the edges of said pocket members.

MYRTLE M. TURNHAM.
